INVENTOR.

BY Jacob Neumann

UNITED STATES PATENT OFFICE

157,778

LUGGAGE HANDLE

Jacob Neumann, Baltimore, Md., assignor to Crown Luggage Co., Inc., Baltimore, Md., a corporation of Maryland

Application January 5, 1950, Serial No. 7,008

Term of patent 14 years

(Cl. D87—2)

To all whom it may concern:

Be it known that I, Jacob Neumann, a citizen of the United States, residing at Baltimore, county of Baltimore and State of Maryland, have invented, a new, original, and ornamental Design for a Luggage Handle, of which the following is a specification, reference being had to the accompanying drawing, forming a part thereof.

I claim:

The ornamental design for a luggage handle, as shown.

JACOB NEUMANN.
